UNITED STATES PATENT OFFICE

WAYLAND D. MICHENER, OF ROSELLE PARK, NEW JERSEY, ASSIGNOR TO THE SINGER MANUFACTURING COMPANY, A CORPORATION OF NEW JERSEY.

MEANS FOR ATTACHING HOOKS AND EYES TO FABRICS.

1,270,966.

Specification of Letters Patent.

Patented July 2, 1918.

Application filed March 3, 1915. Serial No. 11,663.

To all whom it may concern:

Be it known that I, WAYLAND D. MICHENER, a citizen of the United States, residing at Roselle Park, in the county of Union 5 and State of New Jersey, have invented certain new and useful Improvements in Means for Attaching Hooks and Eyes to Fabrics, of which the following is a specification, reference being had therein to the accompanying drawings.

This invention has for its object the attachment of hooks and eyes to fabrics by fastening means applied to the hook-shank and spaced apart along the same sufficiently 15 to prevent twisting or displacement upon the garment when in use. Heretofore, difficulty has been encountered in fastening the hooks in position by machine by reason of the interference of the tongue overlying the greater 20 portion of the length of the hook-shank and opposing a shield against the application of the primary fastening means initially in correct position.

According to the present improvement, the 25 primary fastening means is applied to the hook-shank adjacent the eye at one end of the same adjacent the free end of the tongue, a relative shift being then effected between the fabric and the hook to slide the 30 initial fastening means along the hook-shank and beneath the tongue to the desired position, preferably at the bottom of the throat, after which a final fastening means is applied to the hook-shank within its lateral 35 eyes.

In carrying out the invention, I make use 40 preferably of a sewing machine such as that of the United States Patent to J. J. Sullivan No. 777,564, of December 13, 1904, comprising a rectilinearly reciprocating needle and a laterally jogging work-holder comprising a carrier sustaining a work-supporting plate and a superposed article-holding clamp sustained 45 by an overhanging spring-pressed arm by means of which an article, such as a flat button, may be secured upon a fabric clamped beneath the same within the work-holder. According to the present improvement the 50 article-holding clamp of the former construction is replaced by a special form of clamp mounted upon the spring-pressed arm which is journaled in the present instance within a suitable bearing of a slide-plate 55 movably mounted upon the carrier and pro-

vided with means for retaining it in either of two different positions thereon, whereby the article-holding means may be shifted relatively to the work-supporting plate.

The article holder preferably comprises 60 spaced jaws formed with recesses in their lower faces at the adjacent edges to receive and laterally position the eyed portion of the hook. A spring supporting plate is opposed to said jaws above the work-supporting plate and is formed at its outer end with a slot having a central stitch-supporting tongue and contracted adjacent the free end of said tongue to afford lateral projections underlying said recesses for clamping the 70 eyed portions of the hooks yieldingly within the latter.

The invention will be understood by reference to the accompanying drawings, in which Figure 1 is a rear side elevation of a 75 sewing machine of the well known Singer button sewer type fitted for handling hooks and eyes in accordance with the present improvement, and Fig. 2 is an enlarged perspective view of the work-handling means, 80 with a portion of the machine frame represented in dotted lines. Fig. 3 is a plan of the article-holder and Figs. 3^a and 3^b are respectively transverse and longitudinal sectional views of the holding elements. Fig. 85 4 is a bottom view and Fig. 5 a front end view of the article-holder. Fig. 6 is a plan of the forward portion of the holder with a hook in place therein. Fig. 7 is an enlarged underside view of the bearing slide-plate and catch-lever therefor. Figs. 8, 9 90 and 10 are views representing a portion of fabric and a garment hook applied thereto, and illustrating the fastening operation in its different stages.

The machine frame is constructed with the usual bed-plate 1 from which rises the overhanging bracket-arm 2 having journaled therein the main-shaft 3 to which is operatively connected the rectilinearly reciprocating needle-bar 4 carrying the needle 5 which constitutes one member of the stitch-forming mechanism. Slidably mounted upon the bed-plate 1 is the slide-bar 6 constituting a carrier for the work-holding 100 parts. Rising from one end of the slide-bar is a stud-pin 7 to which is adjustably secured by the clamp-screw 8 the block 9 fitted within a channel in the outer face of the crank-arm 10 which is secured upon one 110

end of the short rock-shaft 11 journaled in a suitable bearing of the bracket 12 rising from the bed-plate. The rock-shaft 11 has upon its opposite end the crank-arm 13 carrying the roller-stud 13' entering a cam-groove 14 in one face of the cam-wheel 15. Through the described connections the cam-wheel is adapted to impart endwise movements to the slide-bar, excepting when the block 9 is set at the neutral point in alignment with the rock-shaft 11, as illustrated in Fig. 2, when the slide-bar is maintained against such endwise movement.

In its forward portion, the slide-bar 6 is secured to a block 16 extending through an aperture in the bed-plate and connected with the slide-plate 17 beneath the latter. The slide-plate 17 is connected by means of the link 18 with one arm 19 of an angle-lever fulcrumed upon the fixed stud-screw 20 and provided with a slotted arm 21 to which is adjustably attached one end of the link 22 having its opposite end connected by a universal joint to the lower arm 23 of a rock-lever fulcrumed at 24 upon the bracket 12 and having an upwardly extending arm 25 carrying the roller-stud 25' entering a cam-groove 26 in the rearward face of the cam-wheel 15. Through the connections thus described, the slide-bar or carrier derives from the cam-wheel lateral jogging movements.

The slide-bar or carrier 6 has rigidly secured upon its forward end the work-supporting plate 27 adapted to rest slidingly upon the usual throat-plate 28 applied to the bed-plate 1, and to sustain the fabric for reception of the articles to be attached thereto.

The bar 6 is provided intermediate its ends with a stud 29 entering an elongated aperture 30 in a slide-plate 31 resting upon said bar and confined thereon by means of the nut 32 applied to the stud 29. The slide-plate 31 is formed in its rearward end with a transverse groove or notch 33 affording a pivotal bearing for the rounded extremity of the downturned lip 34 of the clamp-arm 35 which is normally pressed downwardly toward the bar 6 by means of the flat spring 36 having a forked forward end embracing the stud 37 upon the clamp-arm and an apertured rearward end entered by the clamp-bolt 38 tapped into the block 39 channeled in its upper face to receive the spring 36 and secured by suitable means upon the rearward portion of the slide-bar 6.

Secured upon the bar 6 by means of the screw 40 and dowel-pin 41 is the stop-plate 42. The plate 42 is formed in its under face with a segmental recess provided with the stud-screw 43 upon which is journaled the hub 44 of a finger-lever 45 provided with an angularly extending hooked catch-arm 46 which is adapted for engagement

with a lug 47 upon an adjustable plate 48 having an elongated aperture 48' to receive the shank of the fastening screw 49 by which it is adjustably secured to one edge of the slide-plate 31. The lug 47 not only 70 affords a shoulder for engagement by the catch-arm 46 of the finger-lever but constitutes a projection upon the slide-plate 31 for engagement with the stop-plate 42 to limit the forward movement of the slide-plate. 75

The catch-arm is normally pressed into operative relation with the lug 47 by means of a spring 50 disposed within a recess 51 of the plate 42 and connected at opposite 80 ends respectively with the pin 52 upon the hub 44 and the fixed pin 53 within the recess 51, the catch-arm 46 and lug 47 being suitably beveled to enable the one to pass over the other in their approach to interlocking relation. The slide-plate is normally maintained retracted from the stop-plate 42 by means of a spring 54 attached at one end to a stud-screw 55 depending from the clamp-arm 35 and at the opposite end 90 to the transversely apertured upper end of the stud 29, the slide-plate being drawn backwardly by its described pivotal connection with the clamp-arm.

Pivoted mounted upon the lower face of the clamp-arm 35 by means of the stud-screws 56 are the reciprocally movable clamp-levers 57 having their forward portions downwardly offset to afford work-clamping jaws 57' and provided in their 100 adjacent edges with the notches 58 and 59 to provide clearance for the trust of the needle in the production of the fastening stitches. These jaws are rabbeted at 60 in their lower faces adjacent the notches 59 and are provided with flaring recesses 61 adjacent the notches 58 for reception of the eyed portions of the hooks and eyes. The rabbeted parts 60 afford clearance for the body portion of the eyes, the thread-eyes thereof 105 being received by the recesses 61. Backward of the rabbets 60 the jaws are beveled at 62 along their inner edges to provide ample clearance for the fastening stitches in the shift of the fabric relatively to the hook 110 after the initial stitching operation.

The enlarged outer portion of the clamp-arm 35 is formed with the usual longitudinal slot 63 to receive the shanks of the screws 64 and 65 tapped into the slide-bar 66 provided with the forwardly extending and downwardly offset stop-finger 67. To the under side of the bar 66 is secured the cam-plate 68 formed with the slightly convergent cam slots 69 entered respectively by the studs 70 depending from the clamp-levers 57, whereby the shifting of the bar 66 effects the adjustment of the operative extremity of the stop-finger 67 and simultaneously adjust slightly the spacing apart 125

of the article holding jaws to accommodate garment hooks of different sizes.

The clamp-arm is provided with the usual post 71 having the cross-member 71', and to this post is attached one end of the spring 72 whose opposite end is connected to the screw 65 whereby the latter is maintained yieldingly in contact with the stop-lever 73 fulcrumed upon the clamp-arm by the screw-pin 74 and provided with the segmental slotted cross-member 75 entered by the clamp-screw 76 by means of which it is adapted for adjustment in different positions for setting the article-holder for different sized hooks and eyes.

Secured upon the bottom of the clamp-arm 35 by means of the screw 55 is the foot of a spring-plate 77 having its forward end portion downwardly and forwardly offset to afford a yielding support which is opposed to the bottoms of the article-holding jaws adapted for pressing the hook or eye within the recesses therein for a stitching operation. This plate is provided in its forward end with a longitudinal slot 78 which is contracted at its forward end to form the lateral extensions 79 underlying the recessed and rabbeted edges of the jaws 57' and having extending from its inner end the central stitch-supporting tongue 80 which is slightly upwardly and forwardly inclined, as represented in Fig. 3^b. In the insertion of a hook within the holder, the shank is passed between the jaws 57' and above the tongue 80 into contact with the stop-finger 67, the lateral thread-eyes being received by the recesses 61, as represented in Fig. 6. The eyed portions of the hook are thus maintained seated and held frictionally within the recesses 61 by pressure of the spring-plate projections 79, the shank portion lying above the tongue 80.

The machine is provided with the usual clamp-operating rock-lever 81 fulcrumed upon the bracket-arm and engaging at its forward end a collar 82 upon the lifting bar 83 journaled within the head of the bracket-arm and provided at its lower end with a collar 84 having a backwardly extending arm 85 extending beneath the cross-member 71' of the post 71 by means of which the article-holder may be raised and lowered in opposition to the spring 36 for introduction and removal of the fabric.

The machine is shown provided with a stop-motion of well known construction by means of which the period of operation of the stitch-forming mechanism is controlled for production of groups of tacking or fastening stitches of predetermined number.

In the use of the machine, the article-holder is raised, and a hook or eye inserted therein with its thread-eyes in register with the outer needle clearance notches 58 of the jaws 57', after which the fabric is intro-

duced beneath the same and the work-supporting plate 27 and the work-holder is closed.

The slide-plate 31 being held in its forward position by the catch 46, as represented in Fig. 2, and the clamp-arm correspondingly positioned to locate the notches 59 in register with the needle, the machine is set in operation and a series of fastening stitches *s* applied to the hook-shank adjacent but outside of its thread-eyes, as represented in Fig. 8, wherein the hook *h* is shown secured by a single group of initial fastening stitches upon a section of fabric *m*. The clamp-arm is then wholly or partially lifted and the fabric *m* shifted backwardly thereon whereby the fastening stitches *s* are slid along the hook-shank and beneath the tongue *h'*, as represented in Fig. 9.

The finger-lever 45 is now manually shifted to disengage the catch-arm 46 from the lug 47, whereby the article-holder is permitted to recede under the action of the spring 54 to position the thread-eyes *h''* of the hook within the range of action of the needle, after which the machine is again operated to produce a second group of fastening stitches *s'*, as represented in Figs. 6 and 10.

The function of the stitch-supporting tongue is to support the hook-shank when shifting the fabric relatively thereto so as to prevent its getting under the stop-finger 67; and this tongue is bent upward slightly so as to prevent its catching in the fabric when the latter is shifted to move the initial fastening stitches beneath the tongue of the hook.

It is obvious that in the shifting of the garment hook or eye within its holder from one to the other of the stitching positions the entire work-holder, including the work-supporting plate 27, might be moved in unison, but for the sake of simplicity of construction, the upper clamp-arm is shifted upon and relatively to the slide-bar or carrier 6. This may be effected by the operator's pressing the post 71 forwardly in opposition to the spring 54 preparatory to a fastening operation, for engagement of the catch-arm 46 with the lug 47, and by disengagement of the catch-arm from the lug 47 before the application of the final group of fastening stitches.

The article-holder as thus described is equally adapted for receiving either garment hooks or eyes, the only difference in its mode of manipulation being the maintenance of the holder continuously in its final stitching position for handling eyes in order that the single group of fastening stitches will be applied through its thread-eyes.

From the foregoing description, it is

evident that the mechanism disclosed herein is susceptible of considerable variation in construction without departure from the invention.

5. Having thus set forth the nature of the invention, what I claim herein is:—

1. In a machine for attaching garment hooks to fabrics, in combination, article attaching mechanism including a reciprocating fastening inserting element, a work-support, means above said work-support for pressing the fabric against the latter, said means including opposed hook-supporting elements adapted to position the hook for reception of initial fastening means to be applied about the hook-shank outside of the eyes, means for lifting said hook-supporting elements to release the fabric to permit the slipping of the initial fastening means into a position adjacent the bend of the hook, and means for effecting a shift of said hook-supporting elements laterally of the fastening inserting element, while maintaining control of the hook, to shift and position the hook for reception of subsequent fastening means to be applied through the eyes.

2. In a machine for attaching garment hooks to fabrics, in combination, article attaching mechanism including a reciprocating fastening inserting element, a work-support, means above said work-support for pressing the fabric against the latter, said means including opposed hook-supporting elements adapted to position the hook for reception of initial fastening means to be applied about the hook-shank outside of the eyes, means for lifting said hook-supporting elements to release the fabric to permit the slipping of the initial fastening means into a position adjacent the bend of the hook, and means for effecting a shift of said hook-holding elements relatively to said work-support, while maintaining control of the hook, to shift and position the hook for reception of subsequent fastening means to be applied through the eyes.

3. In a machine for sewing on hooks, in combination, stitch-forming mechanism including a reciprocating needle, a work-support, means for effecting relative lateral jogging movements between said needle and work-support, means above the work-support for holding a hook above the fabric so as to permit the stitching mechanism to sew a loop around the hook-shank between the end of the hook-bill and the eyes, means for shifting said hook-holding means while maintaining control of said hook to shift said hook to a position for reception of a group of stitches within the eyes, and means whereby release of the fabric may be effected so as to permit the slipping of the loop formed upon the shank into a position adjacent the bend of the hook prior to the

formation of said group of stitches within the eyes.

4. In a machine for sewing on hooks, in combination, stitch-forming mechanism including a reciprocating needle, a vertically movable support, opposed hook-gripping elements carried by said support and adapted to grip the hook throughout the hook-attaching operation, means for relatively positioning said support and needle so that an initial group of stitches may be formed about the hook-shank outside of the eyes, means for stopping the machine after the completion of the initial group of stitches to permit said stitches to be shifted toward the bottom of the hook-throat, and means for positioning the hook-gripping elements and needle relatively to each other so that a subsequent group of stitches may be formed within the eyes.

5. A work-holder for sewing machines comprising spaced jaws formed with recesses in their lower faces at the adjacent edges, and a spring supporting plate opposed to said jaws and extending beneath said recesses and provided with an intermediate stitch-supporting tongue.

6. A work-holder for sewing machines comprising spaced jaws formed with recesses in their lower faces at the adjacent edges, and a spring supporting plate formed at its outer end with a slot having a central stitch-supporting tongue and contracted adjacent the free end of said tongue to afford lateral projections underlying said recesses.

7. A work-holder for sewing machines comprising a carrier and an article-holder mounted thereon for movement relatively thereto while maintaining control of the article, and means for securing the article holder in different operative positions upon the carrier.

8. A work-holder for sewing machines comprising a carrier, an article-holder movably mounted thereon, a spring for retaining said article-holder in one position upon said carrier, and a latch for maintaining said article-holder in another operative position thereon.

9. A work-holder for sewing machines comprising a carrier, a work-supporting plate secured in fixed position thereon, an article-holder mounted upon said carrier for movement relatively thereto while maintaining control of the article, means for securing said article-holder in different operative positions upon the carrier, and a spring for pressing said article-holder upon the work-supporting plate.

10. A work-holder for sewing machines comprising a carrier, a work-supporting plate secured in fixed position thereon, a slide-plate mounted upon said carrier and provided with a bearing, a clamp-arm journaled at one end in the bearing of said slide-

plate and provided in its opposite end with article-holding means, a spring applied to said clamp-arm for pressing it normally toward the work-supporting plate, and means 5 for shifting said slide-plate upon said carrier.

11. A work-holder for sewing machines comprising a carrier, a work-supporting plate secured in fixed position thereon, a 10 slide-plate mounted upon said carrier and provided with a bearing and with a shoulder, a clamp-arm journaled at one end in the bearing of said slide-plate and provided in its opposite end with article-holding means, 15 a spring applied to said clamp-arm for

pressing it normally toward the work-supporting plate, a spring for yieldingly maintaining said slide-plate in one position upon said carrier, and a catch-lever adapted for engagement with the shoulder of the slide- 20 plate for maintaining the latter in a different position upon the carrier.

In testimony whereof, I have signed my name to this specification, in the presence of two subscribing witnesses.

WAYLAND D. MICHENEN.
